ATTORNEYS

UNITED STATES PATENT OFFICE.

ERNEST C. COLE, OF CHICAGO, ILLINOIS.

DESIGN FOR A SHEET-METAL STOVE-BODY.

46,492.

Specification for Design.

Patented Oct. 6, 1914.

Application filed July 29, 1914. Serial No. 853,956. Term of patent 3½ years.

To all whom it may concern:

Be it known that I, ERNEST C. COLE, a citizen of the United States, residing in Chicago, in the county of Cook and State of Illinois, have invented a new, original, and ornamental Design for a Sheet-Metal Stove-Body, of which the following is a specification.

In the accompanying drawing:—Figure 1 is an end view of the stove body showing my

new design. Fig. 2 is a plan view of the same: and Fig. 3 is a side view.

I claim:—

The ornamental design for a sheet metal stove body, as shown.

ERNEST C. COLE.
